CLAIM

The ornamental design for a container, as shown and described.

DESCRIPTION

FIG. 1 is a front perspective view of a container with a neck finish shown in broken lines.

FIG. 2 is a front view of the container of FIG. 1.

FIG. 3 is a rear view of the container of FIG. 1.

FIG. 4 is a left view of the container of FIG. 1.

FIG. 5 is a right view of the container of FIG. 1.

FIG. 6 is a top view of the container of FIG. 1.

FIG. 7 is a bottom view of the container of FIG. 1.

FIG. 8 is a perspective view of identical products of FIG. 1 in a stacked relationship.

FIG. 9 is a front view of identical products of FIG. 1 in a stacked relationship.

FIG. 10 is a front view of an alternative embodiment of the product of FIG. 1 with a dispensing nozzle extended.

FIG. 11 is a perspective view of the embodiment of FIG. 10 with a dispensing nozzle extended and in a pouring configuration; and,

FIG. 12 is a front view of an alternative embodiment of the product of FIG. 1 with a closure cap removed.

The broken lines are shown to indicate unclaimed portions of the container and form no part of the claimed design.
